UNITED STATES PATENT OFFICE.

JAMES EDGAR LEE, OF CHICAGO, ILLINOIS.

DESIGN FOR A HANDLE-BAR HEAD.

SPECIFICATION forming part of Design No. 26,466, dated December 29, 1896.

Application filed October 6, 1896. Serial No. 808,063. Term of patent 7 years.

To all whom it may concern:

Be it known that I, JAMES EDGAR LEE, a citizen of the United States, residing at Chicago, in the county of Cook and State of Illinois, have invented and produced a new and original Design or Useful Shape for a Handle-Bar Head for Velocipedes, of which the following, in connection with the accompanying drawings, is a full, clear, and exact specification.

In the said drawings, Figure 1 is a front elevation of a handle-bar head embodying my design. Fig. 2 is a plan view thereof; and Fig. 3 is a transverse sectional view taken on the lines 3 3, Figs. 1 and 2, looking in the direction of the arrows.

The leading features of my design consist of the stem portion A, having the lateral wings or ears B, and the surmounting knob C. The lower end of the stem A is preferably cylindrical, while the laterally-projecting ears or wings B are approximately flat in plan view, as shown in Fig. 2, and are arranged one pair on each side of the stem A, and the ears of each pair being a slight distance apart, as shown in Fig. 2, for the admission of the ends of the sections of handle-bar to be held thereby. The inner edges of the lateral wings B where they join with the stem A are gradually rounded off into the curved and straight lines of such stem, while the outer ends of such ears are circular or substantially so and have their upper edges adjacent to their in-

ner sides provided with upwardly-extending lips b, which are useful in shielding the hand of the rider from contact with any member that may be located between the ears. The outer surfaces of the ears B are also rounded off at their edges or of substantially convex formation, while a central portion of each ear is provided with a convexed button-like formation b', circular in outline when viewed in side elevation, as in Fig. 1.

Located on the upper end of the stem A above and between the ears B is a circular enlargement D, whose periphery is milled, while its upper side curves gradually toward the stem c of the surmounting knob C, as shown at d. The surmounting knob C consists of the cylindrical stem c, which is of smaller diameter than the stem A, and from the upper end of which project lateral spokes c', four in number, arranged diametrically opposite each other and provided at their slightly-tapered extremities with small globular portions c''.

Having thus described my invention, what I claim as new, and desire to secure by Letters Patent, is—

The new and original design or useful shape for handle-bar heads for velocipedes, substantially as herein shown and described.

J. EDGAR LEE.
